No 11,673

Mar 9, 1880

UNITED STATES PATENT OFFICE.

ALBERT TILT, OF PATERSON, NEW JERSEY.

DESIGN FOR A HANDKERCHIEF.

SPECIFICATION forming part of Design No. 11,673, dated March 9, 1880.

Application filed January 23, 1880. Term of patent 3½ years.

To all whom it may concern:

Be it known that I, ALBERT TILT, of the city of Paterson, in the State of New Jersey, have originated and designed a Pattern for 5 Handkerchiefs, of which the following is a full, clear, and exact description, reference being had to the accompanying photographic copy, making a part of this specification, in which—

A represents a portion of the body or center 10 of the handkerchief, and B a portion of the border.

My design relates more particularly to that description of handkerchiefs usually known as "figured silk handkerchiefs;" and it consists 15 of the ornamentation of the central portion or body, A, of the handkerchief by embroidering or weaving upon it the design or arrangement of sprigs of flowers and leaves set forth and shown in the accompanying photographic copy, 20 the design on the portions of the body of the handkerchief not shown in such photographic copy being a duplication of that on the portion shown.

The border B is divided from the body or

central portion, A, by the narrow stripe d, and 25 is ornamented by embroidering or weaving upon it the design or pattern e, intended to imitate lace. Outside of such design e, and near the outer edge of the border B, is the stripe e, all as shown in the photographic copy. 30

Appropriate colors should be used for the handkerchief and the design; or they may be of the same color, the one being of silk and the other of satin.

Having thus described the pattern for handkerchiefs originated or designed by me, what I claim, and desire to secure by Letters Patent, is—

The design for a handkerchief, consisting of the body or center A, of leaves and flowers, 40 the border B, having the scroll-work e, and the stripes d and e, substantially as described, and shown in the accompanying illustration.

ALBERT TILT.
